UNITED STATES PATENT OFFICE.

JAMES P. RATIGAN, OF WALNUT PARK, CALIFORNIA.

BEAM ADJUSTER.

Application filed December 13, 1926. Serial No. 154,470.

This invention relates to so-called beam adjusters, a mechanism that is employed in the pumping of wells, said mechanism being used for connecting an operating member, such as a walking-beam, to the clamp that holds the polish rod of the pump.

An object of the invention is to permit of displacement of the beam adjuster stem from the walking-beam or other operating member, while, at the same time, insuring against complete disconnection between the operating member and said stem.

Another object is to improve the construction for mounting the stem on the operating member.

Further objects and advantages will appear in the subjoining detailed description.

The accompanying drawings illustrate the invention:

Fig. 1 is a perspective view of a beam adjuster, constructed in accordance with the provisions of this invention, a fragment of the operating member, with which the beam adjuster is associated, being shown in broken lines.

Fig. 2 is a perspective view of the saddle with the locking pin in place.

Fig. 3 is a perspective view of the stem.

Fig. 4 is a perspective view of the bottom plate.

There is provided a saddle comprising a flat plate 5 and upturned flanges 6 along one of the longitudinal edges of the plate. At its opposite ends the plate 5 is provided with longitudinal extending slots 7, the purpose of which will be mentioned hereinafter. From the underface of the plate 5 projects spurs 8 adapted to penetrate the upper face of the operating member, a fragment of which is indicated at A in Fig. 1.

The plate is provided with an opening 9 and the flanges 6 are on opposite sides of said opening. Projecting from the outer faces of the flanges 6 are ears 10 and 11 through which projects a pin 12, said pin serving to close the outer end of the opening 9. The pin 12 has a head 13 at one end adapted to engage the ear 10 and said pin has near its other end a shoulder 14 adapted, when the pin is turned to the position shown in Fig. 1, to engage the ear 11 so as to prevent disengagement of the pin from the ear

11. The ear 11 is provided with a slot 15 that communicates with the bore 16 through which the pin 12 passes in the ear 11. The slot 15 is of sufficient width to permit of the shoulder 14 passing there-through when the pin 12 is turned to the position shown in Fig. 2 and then moved endwise toward the ear 10. The shoulder 14 will prevent withdrawal of the pin 12 from the ear 10.

Seated on the upper face of the plate 5 are flanges 17 that project laterally from a stem 18 and projecting up from said flanges is an eye 19 which may be engaged by a hoisting tackle when it is desired to displace the stem from or replace the stem on the operating member A. The stem 18 is adapted to extend through a vertical slot B in the end of the operating member, in a manner well understood in this art, and the flanges 6 prevent sliding of the flanges 17 off of the plate 5.

The lower end of the stem 18 may be constructed in any suitable manner for connection with the polish rod clamp, not shown. In this instance the lower end of the stem 18 has spaced furcations 20 through which extends a pin 21 held in place by a head 22 at one end and a removable cotter pin 23 near its opposite end. The means for connecting the pin 21 with the polish rod clamp, not shown, may be of any suitable construction and is not illustrated nor described in this specification as it constitutes no portion of the present invention.

There is provided on the under-surface of the operating member A, a bottom plate 24 having at its outer longitudinal edge a flange 25, which, in this particular instance, projects downwardly. The plate 24 is provided near its opposite ends with longitudinal extending slots 26 through which project spurs 27 of hook shaped members 28 which extend vertically along the side faces of the operating member A and have their upper ends engaged in the slots 7. The members 28 have screw threaded onto their upper ends nuts 29 which lie above the plate 5. In this instance, washers 30 are interposed between the nuts 29 and the plate 5. It will be apparent from Fig. 1 that the spurs 27 are driven into the underface of the operating member A.

In assembling the beam adjuster on the operating member, it is desirable to so position it that the stem 18 will hang vertically and be in axial alignment with the polish rod 5 of the pump when the operating member is substantially in horizontal position. Accordingly, in mounting the beam connector on the operating member, the plate 5 will first be placed in position on the upper face 10 of the operating member and then the stem 18 will be placed in position and connected with the polish rod clamp in a manner well understood in this art. If, after thus connecting the stem 18, said stem should not 15 hang vertically when the operating member is substantially horizontal, the plate 5 will be moved lengthwise of the operating member until vertical hanging of the stem 18 is obtained. If the plate has been correctly positioned, the bottom plate 24 will be placed 20 in position against the underface of the operating member and the hookshaped members 28 will then be assembled in position as shown in Fig. 1 and the nuts 29 tightened. 25 In positioning the plate 24, care will be taken to have the flange 25 engage the stem 18 when the operating member is substantially horizontal so that, when the operating member is swinging on the upper half of its up- 30 stroke, the stem 18 will be held against swinging inwardly toward the fulcrum point of the operating member, thus avoiding any appreciable bending of the polish rod. On the lower half of the downstroke of the 35 operating member, the stem 18 is free to swing away from the flange 25 so as to be retained substantially in axial alignment with the polish rod and not interfere with free downward motion of the polish rod. 40 During the pumping operation it sometimes happens that the pump plunger does not descend as quickly as the operating member and in such instances the stem 18 is prevented from becoming entirely disengaged 45 from the operating member, even though the flanges 6 are operated to a lower level than the flanges 17. For, under such circumstances, the stem 18 will be prevented from disengaging the opening 9 in the plate 5 by the pin 12. It is to be noted that the inner 50 faces of the flanges 6 extend aslant downward and inwardly so that, in event of the flanges 17 being unseated from the plate 5 by a quicker descent of the operating member than the stem 18, upon the next subsequent upstroke of the operating member the flanges 17 will be properly guided into position on the plate 5 by the flanges 6.

I claim:

60 1. A beam adjuster comprising a saddle provided with an opening therein extending to one edge of the saddle, means to secure the saddle to an operating member, a stem extending through the opening and provided with flanges loosely seated on the saddle,

and a pin movably mounted on the saddle and extending across the opening to prevent the stem escaping from the opening.

2. A beam adjuster comprising a plate provided with an opening therein extending to one edge of said plate, means to secure the plate to an operating member, a stem extending through the opening and provided with flanges loosely seated on the plate, said plate provided on opposite sides of the opening with upwardly projecting flanges, and movable means connected with the plate and extending across the opening to prevent the stem escaping from the opening when the first mentioned flanges are above the level of the second mentioned flanges.

3. A beam adjuster comprising a saddle provided with an opening therein extending to one edge of the saddle, a stem extending through the opening, means loosely suspending the stem from the saddle, and a member movably connected with the saddle and extending across the opening to prevent the stem escaping from the opening.

4. A beam adjuster comprising a saddle provided with an opening therein, a bottom plate, hook-shaped members connecting the saddle and bottom plate, and a stem supported on the saddle and extending through the opening.

5. A beam adjuster comprising a saddle provided with an opening therein, a bottom plate, hook-shaped members connecting the saddle and bottom plate and provided with spurs passing upwardly through the bottom plate, and a stem supported on the saddle and extending through the opening.

6. A beam adjuster comprising a saddle provided with an opening therein, a stem swingingly supported on the saddle and extending through the opening, a bottom plate limiting swinging of the stem in one direction, and means connecting the saddle and bottom plate.

7. A beam adjuster comprising a saddle provided with an opening therein and provided with slots near its ends, a stem swingingly supported on the saddle and extending through the opening, a bottom plate limiting swinging of the stem in one direction and provided with slots near its ends, hook-shaped members passing through the slots in the saddle and provided with spurs passing through the slots in the bottom plate, and nuts threaded onto the hook-shaped members above the saddle.

8. A beam adjuster comprising a saddle provided with an opening therein extending to one edge of the saddle, a stem swingingly supported on the saddle and extending through the opening, ears on the saddle on opposite sides of the opening, a pin extending through the ears and provided with a head at one end and with a laterally projecting shoulder near its opposite end, the

ear adjacent to the shoulder provided with a slot communicating with the bore of said ear, said slot being of sufficient width to admit of the passage therethrough of the shoulder.

member, a bottom plate limiting swinging of the stem in one direction, and means for securing the bottom plate to the operating member.

9. A beam adjuster comprising a stem adapted for connection with an operating

Signed at Los Angeles, California, this 1st day of December, 1926.

JAMES P. RATIGAN.
